UNITED STATES PATENT OFFICE.

JOHN ERNEST BLOUNT, OF LOUISVILLE, KENTUCKY.

ELECTRIC HUMIDOR.

1,424,979.

Specification of Letters Patent. Patented Aug. 8, 1922.

Application filed March 13, 1922. Serial No. 543,439.

To all whom it may concern:

Be it known that I, JOHN ERNEST BLOUNT, a citizen of the United States, residing at Louisville, in the county of Jefferson and State of Kentucky, have invented a new and useful Electric Humidor, of which the following is a specification.

The object of my invention is to provide a convenient device to be used in cigar cases for moistening the cigars; or to be placed in any case where goods are kept which require a certain degree of moistening; and to provide a convenient apparatus for this purpose having the novel combination and arrangement of parts disclosed.

I attain these and other objects of my invention by the mechanism illustrated in the accompanying drawings, in which—

Figure 1 is a top plan of the invention; Fig. 2 is a longitudinal vertical section on line 2—2 of Fig. 1;

Fig. 3 is a detail view of the electrodes with cover 10 removed;

Fig. 4 is a bottom plan view of the invention;

Fig. 5 is an end elevation, partly in section to show details of the disposition of the electrodes and binder screws; and

Fig. 6 is a detail perspective view of the electrodes removed.

Like numerals indicate like parts in each of the several views.

Referring to the accompanying drawings, I provide a suitable base 1 of white porcelain or similar non-conducting material recessed to receive an inverted bowl or water container 3. This container will vary in diameter in proportion to the size of the base. I provide a feed groove or channel 4 in communication with the interior of chamber 3, said channel leading into a suitable well such as the rectangular pocket or well 5 shown in Fig. 3. This well which has a water heating compartment also varies in size in proportion to the size of the base.

Extending into the well 5 I provide a long electrode 6 and a short electrode 7, which are positive and negative, and are constructed of brass or other non-rusting materials. These electrodes are made in a stair-step shape in order to fit in the small well. Between the free ends of the electrodes 6 and 7 is a suitable gap 18. Short electrode 7 is attached to base 1 by the binder screw 9; and long electrode 6 is attached to base 1 by the binder screw 8. Mounted over the well 5 I provide

a suitable cover 10 having the opening 11 for the escape of the moisture from the apparatus. Cover 10 is attached to base 1 by means of suitable attaching screws 12. I provide suitable depressions 13 in the bottom of base 1 to receive the threaded ends and nuts of both the binder screws 8 and 9 and the attaching screws 12, so that the surface of the bottom of the base member 16 will have no projections.

I provide a suitable attaching plug 14 of conventional design for bringing the electric current in from any suitable source of current. I provide suitable wires 16 electrically connecting the plug 14 with a suitable conventional electric switch 15, as shown in Figs. 1, 2 and 4. And I provide wires 17 electrically connecting the binder screws and electrodes with the switch 15, as will be understood by reference to Fig. 4.

In operation the current passing through from one electrode to another across gap 18 heats the water in the well 5 and the steam rising through the cover opening 11 provides moisture which moistens the tobacco or other goods contained in the case in which this apparatus is also placed. In order to get the proper amount of steam or to regulate the steam, the switch 15 is utilized to control the amount of electric current that passes across the gap 18. The water in the inverted bowl 3 is held in place by vacuum and feeds gradually through the channel 4 into the well 5 as the water there is evaporated.

The apparatus is removed or the switch is turned off when the goods have been well moistened.

What I claim is:

1. In an electric humidor, the combination of a recessed base, a water containing bowl mounted in the recessed portion of said base, the base having a well spaced from the bowl, the base also having a channel communicating from the interior of the bowl to the well, and electrodes extending into the well and spaced apart to form a suitable gap.

2. In an electric humidor, the combination of a recessed base, a water containing bowl mounted in the recessed portion of said base, the base having a well spaced from the bowl, the base also having a channel communicating from the interior of the bowl to the well, electrodes extending into the well and spaced apart to form a suitable gap.

- gap, a switch with which said electrodes are electrically connected, and means for electrically connecting the switch with a suitable source of current.
5. 3. In an electric humidor, the combination of a base of non-conducting material, an inverted bowl mounted on said base, a water channel opening out of the bowl, a well into which the water channel leads, 10 electrodes extending into the well and having their free ends spaced apart, one of said electrodes being longer than the other to position the gap at one side of the end of the channel, a switch with which the electrodes are electrically connected, and means 15 for electrically connecting the switch with a suitable source of current.
4. In an electric humidor, the combination of a recessed base of non-conducting material, an inverted bowl mounted on the
- recessed portion of said base, the base having a well formed at a distance from the bowl, a feed groove leading from the bowl to the well and having an opening for the escape of moisture, electrodes extending into the wall, means securing said electrodes on said base and electrically connecting same with a switch, a switch, and means electrically connecting the switch with a suitable source of current. 25
5. In an electric humidor, the combination of a recessed base, a bowl on said base, a well supplied with water from the bowl, electrodes extending into the well, said electrodes being of stair-step shape, means electrically connecting the electrodes with a switch, a switch, and means electrically connecting the switch with a suitable source of current, substantially as shown. 30
- JOHN ERNEST BLOUNT.
